CLAIM

The ornamental design for a doll, as shown and described.

DESCRIPTION

FIG. 1 is a front view in elevation of a doll of the present invention.

FIG. 2 is a side view in elevation of the doll's right side of the doll design of the present invention.

FIG. 3 is a rear view in elevation of the doll of the present invention.

FIG. 4 is a side view in elevation of the doll's left side of the doll design of the present invention.

FIG. 5 is a top view in plan of the doll of the present invention; and,

FIG. 6 is a bottom view in plan of the doll of the present invention.

The broken line showing the hat is for illustrative purposes only, and forms no part of the claimed design.
